UNITED STATES PATENT OFFICE.

RICHARD L. MANGRUM AND ROLAND O. TOEVS, OF LOS ANGELES, CALIFORNIA.

TANK.

Application filed June 23, 1923. Serial No. 647,219.

To all whom it may concern:

Be it known that we, RICHARD L. MANGRUM and ROLAND O. TOEVS, citizens of the United States, residing at Los Angeles, in the county of Los Angeles and State of California, have jointly invented new and useful Improvements in Tanks, of which the following is a specification.

Our invention relates to tanks and it is an improvement upon our tank disclosed in our application for United States Letters Patent filed December 21, 1922, Serial No. 608,163, which tank is composed of a plurality of sections welded together and reinforced at their joints, providing a solid structural tank which is strong, durable, fluid tight, fire proof and economical in construction.

The main object of our invention is to provide improved reinforcing means at the joints between the sections, thus providing a stronger, more durable and more efficient tank than our former tank above mentioned, or any other known tank.

Other objects and advantages will appear hereinafter, and while we show herewith, and will describe a preferred form of construction, we desire to be understood that we do not limit ourselves to such preferred form, but that various changes and adaptations may be made therein without departing from the spirit of our invention as hereinafter claimed.

Referring to the drawing which forms a part of this specification:

Fig. 1 is a plan view of our tank.

Fig. 2 is a vertical transverse section of our tank taken on line 2-2 of Fig. 1.

Fig. 3 is an enlarged fragmentary vertical sectional view of our tank illustrating the joint for securing the cover to the body of the tank.

Fig. 4 is a fragmentary sectional view taken on line 4-4 of Fig. 2 showing one of the vertical joints between the body sections.

Fig. 5 is a fragmentary sectional view taken on line 5-5 of Fig. 2 showing the joint between the body and the bottom of the tank.

Fig. 6 is a view similar to Fig. 5 of a modified form of joint between the body and bottom of the tank.

Fig. 7 is a view similar to Figs. 5 and 6 of another modified form of joint between the bottom and body of the tank.

In the drawing 1 indicates the bottom of my tank, 2 the body, and 3 the top thereof. The bottom 1 is composed of a plurality of metal plates 4, 5, 6 and 7, the plates 4 and 5, the plates 4 and 6, and the plates 5 and 7 being joined together at their meeting side edges by joints 8 comprising upturned flanges 9 at said edges which flanges are welded together at their upper edges as indicated at 10. The joint 8 uniting the plates 4 and 5 extends diametrically of the bottom 1 and the joints uniting the plates 4 and 6 and the plates 5 and 7 extending parallel to said diametrical joint uniting plates 4 and 5. The adjoining ends of the plates 4, the plates 5, the plates 6 and the plates 7 are also united by joints 8. The construction of the top 3 is the same as the construction of the bottom as above described and a detailed description of said top is therefore not necessary.

The body 2 is composed of a plurality of superimposed annular units 11. Each unit 11 comprises a plurality of arcuate plates 12 joined together at their vertical edges by joints 13, each of which joints comprises outturned flanges 14 on adjoining edges of said plates and a T-bar 15, the leg member 16 of said bar extending outwardly between said flanges and the head member 17 of said bar resting against the inside of said plates 12, said leg member 16 of said T-bar and the flanges 14 being welded together at their outer edges as at 18, and said head member 17 of said T-bar being spot welded to the inside of the plates 12 as at 19. The units 11 have formed at the lower and upper edges of the plates 12 external annular flanges 20 and 21 respectively. The ends of the joints 8 at the periphery of the bottom 1 are cut away as at 22 to accommodate an annular angle iron 23, the base flange 24 of which angle iron being external of its vertical flange 25.

25 and said base flange resting upon said bottom with its outer peripheral edge coinciding with the peripheral edge of said bottom. The lowermost unit 11 telescopes 5 over the vertical flange 25 of angle iron 23 and the base flange 20 of said unit rests upon the base flange 24 of said angle iron with its outer edge coinciding with the outer edge of said base flange 24 and the 10 bottom 1. The outer edges of the bottom 1, flange 24 and said flange 20 are welded together as indicated at 26 thus forming a most effective reinforced joint 27 between the bottom 1 and the lowermost unit 11. 15 The angle iron 23 is spot welded at its upper edge to the inside of the lowermost unit 11 as at 28. The superimposed units 11 are united together by joints 30, each of 20 which comprises the flange 21 of one unit, the flange 20 of the unit above, and an annular T-iron 31, the leg flange 32 of said T-iron being external of the vertical head flange 33 and extending between said flanges 20 and 21, with said unit telescoped over 25 said head flange. The outer edges of said flanges 20, 21 and 32 coincide and are welded together as indicated at 34, while the edges of the head flange 33 are spot welded to the inside of said units 11, as 30 at 35. The joints 8 between the bottom plates 4 and 5 are cut away at the center of the bottom 1 to receive a disk 36, which is welded to the inside of said bottom centrally thereof. A post 37 extends centrally 35 longitudinally of the tank and rests on and is welded at its lower end to the disk 36.

A disk 38 is welded on the upper end of post 37. The upper end of the post 37 is centrally secured in position by radial 10 angle bars 39, the inner and outer ends of the vertical flanges 40 of which bars being cut away a short distance as at 41 and 42 respectively, so that the end portions of the upper horizontal flanges 43 of said angle irons rest respectively upon the disk 38 and the upper flange 21 of the uppermost unit 11, and are welded to said disk and said flange.

50 Arcuate angle irons 44 are placed between the outer ends of the angle irons 39 with their horizontal flanges 45, which are external of their vertical flanges 46, resting upon said flange 21 of said uppermost unit 11 and with their vertical flanges 46 resting against the inside of said uppermost unit, the outer edge of said flanges 45 and 21 coinciding. The cover 3 rests upon the flanges 45 of angle irons 44 and the flanges 43 of angle bars 40 with the edge of said 55 cover coinciding with the outer edges of flanges 45 and 21 and the outer ends of angle bars 39 and said outer edge of said cover is welded to the outer edges of the flanges 45 and 21 and to the outer ends of 60 said angle bars and the outer edges of said 65

flange 21 as indicated at 47, thus forming an effective joint 48 between said cover and the upper edge of the uppermost unit 11.

The angle irons 44 are spot welded at their lower edges to the inside of said unit 70 11 as at 49 and at their corners to the under side of cover 3 as at 50.

A manhole 51 may be located in the side of the tank at the bottom thereof. Said manhole may consist of a box-shaped member 52 open at its inner end and fitted at 75 said end within an opening 53 in the wall of the lowermost unit 11 and detachably closed at its outer end by a plate 54, which is bolted by bolts 55 to an external flange 56 on said outer end. An inturned flange 57 may be formed around the inside of the opening 53 and the inner ends of the upper and side walls of the member 52 welded to said flange 57, while the lower wall of 80 said member may be welded to the bottom 1.

A vertical ladder 60 may be located at one side of the tank, which ladder may be welded at its lower end to joint 27 and at its upper end to joint 48, and braced intermediate its ends by braces 61 welded at 90 their inner ends to joints 30 and at their outer ends to the ladder.

In the modified form of joint 27 the flange 20 rests directly upon the bottom 1 and an annular angle iron 62 fits within the unit 11 with its vertical flange 63 against the wall of said unit and its lower horizontal flange 64, which extends internally from 95 said vertical flange, resting upon the bottom 1. The outer edges of the flange 20 and the bottom 1 are welded together as indicated at 65. The edges of the flanges 63 and 64 of the angle iron 62 are welded to the unit 11 and the bottom 1 as at 66 and 67. 100

In the modified form of joint 27 shown in Fig. 7 an annular T-iron 70 is substituted for the angle iron 23, the head member 71 of said angle iron resting upon the bottom 1 with its outer edge flush with the outer edge of said bottom, and the unit 11 being telescoped over the vertical flange 72 of said T-iron with the flange 20 of said unit resting upon the outer arm of the head member 71, with the outer edge of said 115 flange coinciding with the outer edge of said arm and the bottom 1, which outer edges are welded together as indicated at 73. The upper edge of the member 72 of the T-iron 70 is spot welded at 74 to the 120 inside of the unit 11, while the inner edge of the head member 71 of said T-iron is spot welded to the bottom 1 as at 75.

We claim as our invention:

1. A tank composed of a plurality of sections, flanges on the adjoining edges of said sections, flanged members having one flange fitting between the flanges on said sections and another flange fitting against the inside of the tank, said section flanges and said 125

flange therebetween being welded together at their edges.

2. A tank composed of a plurality of sections, flanges on the adjoining edges of said sections, flanged members having one flange fitting between the flanges on said sections and another flange fitting against the inside of the tank, said section flanges and said flange therebetween being welded together 10 at their edges, the other flange of said flanged member being spot welded to the tank sections.

3. A tank composed of a plurality of sections, flanges on the meeting edges of the 15 sections, and T-irons arranged with their leg members fitting between the flanges of adjoining sections, and their head members engaging said sections, the edges of said flanges and the leg members therebetween 20 being welded together.

4. A tank including a bottom, a body, an angle iron resting with one flange upon said bottom at the periphery thereof, the lower edge of said body telescoping over the other 25 flange of said angle iron, a flange formed on the lower edge of said body and resting upon the flange of said angle iron which rests upon said bottom, the edges of said latter angle iron flange, said bottom and 30 said flange on said body being welded together.

5. A tank including a bottom, and a body, said body comprising a plurality of annular superimposed units, the lowermost unit resting 35 upon and being united to said bottom, flanges on the meeting edges of said units, T-irons arranged with their leg members fitting between the flanges of adjoining units and their head members engaging said units, the edges of said leg members and said 40 flanges being welded together.

6. A tank including a bottom, and a body, said body comprising a plurality of annular superimposed units, the lowermost unit resting 45 upon and being united to said bottom, flanges on the meeting edges of said units, T-irons arranged with their leg members fitting between the flanges of adjoining units and their head members engaging said units, the edges of said leg members and said 50 flanges being welded together, said head members being spot welded to said units.

7. A tank including a bottom, a body, 55 an angle iron resting with one flange upon said bottom at the periphery thereof, the lower edge of said body telescoping over the other flange of said angle iron, a flange formed on the lower edge of said body and resting upon the flange of said angle iron, which rests upon said bottom, the edges of 60 said latter angle iron flange, said bottom and said flange on said body being welded together, said angle iron being spot welded 65 to said body.

8. A tank composed of a plurality of sections, flanges on the meeting edges of the sections, and T-irons arranged with their leg members fitting between the flanges of adjoining sections, and their head members 70 engaging said sections, the edges of said flanges and the leg members therebetween being welded together, said head members being spot welded to said sections.

9. A tank including a bottom, a body 75 composed of a plurality of superimposed annular units, the lowermost unit being united to said bottom and said units being united to each other, each unit comprising a plurality of arcuate plates, flanges on the 80 meeting vertical edges of said plate, and T-irons arranged with their leg members extending between said meeting flanges and their head members engaging said plates, the edges of said leg members and said 85 flanges being welded together.

10. A tank including a bottom, a body composed of a plurality of superimposed annular units, the lowermost unit being 90 united to said bottom and said units being united to each other, each unit comprising a plurality of arcuate plates, flanges on the meeting vertical edges of said plate, and T-irons arranged with their leg members 95 extending between said meeting flanges and their head members engaging said plates, the edges of said leg members and said flanges being welded together, and said head members being spot welded to said plates.

11. A tank comprising a bottom, a body united to said bottom, a disk welded to the center of said bottom and a post welded at its lower end to said disk.

12. A tank comprising a bottom, a body 105 united to said bottom, a post united at its lower end to said bottom, a disk secured on the upper end of said post, and radial braces welded to said disk at their inner ends and to said body at their outer ends.

13. A tank comprising a bottom, a body 110 united to said body, a flange on the upper end of said body, a post united at its lower end to said bottom, a disk secured on the upper end of said post, angle iron braces 115 having their vertical flanges cut away a short distance at their ends so that their horizontal flanges rest at their ends respectively upon said plate and said flange on the upper end of said body, said horizontal 120 flanges being welded at their ends to said disk and said body flange.

14. A tank comprising a bottom, a body 125 united to said body, a flange on the upper end of said body, a post united at its lower end to said bottom, a disk secured on the upper end of said post, angle iron braces having their vertical flanges cut away a short distance at their ends so that their horizontal flanges rest at their ends respec- 130

4

tively upon said plate and said flange on the upper end of said body, said horizontal flanges being welded at their ends to said disk and said body flange, angle irons between said braces resting with one flange upon said body flange and with their other flange against said body, a cover resting upon said braces and said angle irons, the edge of said cover being welded to the edges of the angle iron flanges resting upon said body flange, the ends of said braces, and the edge of said body flange.

RICHARD L. MANGRUM.
